[57] CLAIM

The ornamental design for a combined auxiliary vehicle brake light and turn signal, as shown and described.

DESCRIPTION

FIG. 1 is a top, front perspective view of a combined vehicle auxiliary brake signal light and turn signal showing my new design;

FIG. 2 is a bottom, rear perspective view thereof;
FIG. 3 is a front elevational view thereof on an enlarged scale;

FIG. 4 is a right side elevational view thereof on an enlarged scale, the left side being a mirror image;

FIG. 5 is a front perspective view of a second embodiment of my new design; and

FIG. 6 is a fragmentary perspective view of a portion of the front lens of the second embodiment on a greatly enlarged scale to show the diamond pattern on the lens. The second embodiment differs from the first embodiment only by the raised pattern on the front surface of the lens.

FIG. 1

FIG. 2

FIG. 3

FIG. 6

FIG. 4

FIG. 5
